UNITED STATES PATENT OFFICE.

DELBERT I. WILSON, OF COLUMBUS, OHIO, ASSIGNOR TO AULD'S INCORPORATED, OF COLUMBUS, OHIO.

RING MANUFACTURE.

Application filed May 22, 1925. Serial No. 32,227.

This invention relates to the manufacture of finger rings and has special reference to the production of seal or initial rings, the primary object being the provision of simple means whereby to produce a finished ring in one piece and in an endless seamless circle, and another object being the provision of means whereby a design may be applied to the ring easily and expeditiously and will appear clearly in the finished ring. The invention is illustrated in the accompanying drawings and will be hereinafter fully described, the novel features being particularly pointed out in the appended claims.

In the drawings, Figure 1 is a perspective view of the dies employed in the practice of my invention, the dies being separated,

Figures 2 and 3 are vertical sections, taken in planes at a right angle to each other, showing a ring and mandrel in position between the dies as before pressure is applied,

Figure 4 is a view in section showing another embodiment of the invention.

Fig. 5 is a detail of the mandrel.

The ring blank or unfinished ring 1 is first produced by casting, and is then placed between the dies 2 and 3 to receive its final shape and have the surface ornamentation produced by the application of pressure. The dies 2, 3, are hard steel blocks of counterpart form, each having a groove 4, of semi-circular cross section, extending across its working face and also having a matrix 5 formed across said groove, the floor or bottom of each matrix having engraved, or otherwise formed, therein so much of the ornamental design as is to appear on one shank of the ring. Each matrix is of proper form to receive one shank of the ring, and a mandrel 6 of hard steel is inserted through the ring and is accommodated in the grooves 4.

In practicing the invention, in the manner illustrated in Figures 1, 2 and 3, the ring blank is cast slightly oversize so that it will not seat perfectly in the matrices in the die blocks and will rest on the wall of the matrix in the lower die. The blank is placed on the mandrel 6 and the mandrel then laid in the groove in the lower die, thus retaining the ring over and partly in the transverse matrix in the die, and it may be here noted that the mandrel is of a diameter to fit snugly in the ring and is very slightly

tapered in order to facilitate its withdrawal from the ring. The upper die is placed over the lower die and the ring and mandrel, being held in proper relation thereto by the usual guide pins 7, so that the ring enters its transverse matrix and the mandrel engages its groove, the mating working faces of the dies being about one-quarter of an inch apart. Pressure is now applied to the dies so that their working faces are forced to within a few thousandths of an inch of each other, thereby compressing the ring about the mandrel and in the matrices, driving the metal of the ring into intimate contact with the walls of the matrices and forming upon the ring whatever design may have been produced in the matrices. After the ring is removed from the dies, it will be necessary to merely remove a few thin overflow fins which may be formed thereon and mount a top, if a top is desired.

In the embodiment of the invention illustrated in Figure 4, the blank is cast somewhat undersize so that it will freely enter the transverse recesses in the dies. The mandrel 8 is longer than the mandrel 6 and is formed with a cylindrical end portion 9, whereby it may be easily engaged in the ring, and with an intermediate portion 10 having a well-defined taper. The dies with the ring therein are placed in the holder 11 and the mandrel then engaged through the ring and the grooves of the dies, after which pressure is applied to the mandrel to drive its tapered portion through the ring thereby expanding the ring within the matrices of the dies and transferring to the ring the designs of the dies.

It will be readily noted that I cast the ring with an excess of metal, as at 12, on its bottom which is that portion lying at the inner side of the finger when the ring is worn. This surplus provides for stretching the ring by known methods to fit larger fingers.

According to this invention, the ring is not rotated within or between the dies but is retained therein by a mandrel so that the application of pressure to either the mandrel or the dies will force the ring into intimate contact with the engraved surfaces of the dies and effectually produce the desired designs on the shanks of the ring. It is also to be noted that the plane of the ring when it is in the dies is at right angle to

the working faces of the dies and that each die carries one-half of the complete design so that when the pressure is withdrawn the dies may be separated without any defacement or other impairment of the ring. While I have referred particularly to rings having ornamented shanks, it is to be understood that the invention is not limited to the production of such rings but may be applied 10 to the manufacture of other styles of rings and especially men's heavy gold rings for individual engraving.

Having fully described my invention what I claim as new and desire to secure by 15 Letters Patent, is:—

1. Means for manufacturing finger rings comprising a pair of dies to receive a cast seamless ring between them with the plane of the ring at a right angle to the plane of 20 the working faces of the dies, the working face of each die having a transverse matrix conforming to one-half of the ring and having a design to be transferred to one shank of the ring and a groove extending across

the face of the die at a right angle to the 25 matrix, and a non-compressible non-expandable mandrel fitting in the grooves in the dies and passing through a ring received within the matrices.

2. Means for manufacturing finger rings 30 comprising a pair of dies each having a groove extending across its face and also having a matrix at a right angle to said groove, the matrix conforming to one-half of a seamless cast ring to be received therein 35 at a right angle to the working face of the die and bearing one-half of a design to be transferred to the ring, and a mandrel extending through the grooves and across and between the matrices to retain the ring in 40 engagement with the matrices whereby upon application of pressure the ring will be forced into intimate contact with the surfaces of the matrices and the design of the 45 matrices transferred to the ring.

In testimony whereof, I have signed this specification.

DELBERT I. WILSON.
